UNITED STATES PATENT OFFICE

2,576,732

TRUCK AND WAGON HOIST

Raymond M. Ulrich, Roanoke, III.

Application July 21, 1948, Serial No. 39,941

5 Claims. (Cl. 254—91)

1

The present invention relates to a vehicle hoist or lifting device and more particularly to a hydraulically operated device for lifting one end of a wagon or truck.

It is an object of the present invention to provide an improved hoist which will produce a minimum movement of the end of the wagon or truck, of standard or common wheel base, which remains on the ground.

Another object of the present invention is to provide an improved vehicle hoist requiring a minimum of space and yet providing maximum stability of operation.

A still further object of the present invention is to provide an improved truck and wagon hoist of the hydraulic type having equal lifting power on each side.

Still another object of the present invention is to provide an improved vehicle hoist of the hydraulic operated type which may be utilized with different width cradles.

Still another object of the present invention is to provide an improved hydraulically operated vehicle hoist which may utilize hydraulic cylinders and lifting arms such as those used in tractor loaders.

Other and further objects of the present invention subsequently will become apparent by reference to the following description taken in conjunction with the accompanying drawings wherein:

Fig. 1 is a perspective view of the hoist in raised position;

Fig. 2 is a side view of the hoist in raised position; and

Fig. 3 is a detailed view of the equalizer crank-shaft.

Referring to the drawing it will be seen that the vehicle hoist constructed in accordance with the present invention employs two similar vertical frame members 11 and 12 positioned parallel to each other. Since both side frame members are similar only one of these frame members will be described in detail. Each frame member includes a base 13 formed of channel iron or similar construction. Near the center of the channel 13 at opposite sides a pair of support plates 14 is provided each support plate having therein an opening or hole 15 for receiving a fastening bolt, or other securing device. Mounted on the side of the channel 13 and resting upon the support plates 14 are parallel vertical support members 16 and 17 formed of pipe or tubing. At the tops of the vertical support members 16 and 17 suitable bearing openings are provided for receiving a shaft or bolt 18 which supports a lifting arm 19. The inner vertical member 16 is reinforced by tubular member 21 interconnecting the top of the member 16 with the channel base 13. The top of the other vertical member 17 is interconnected with both ends of the channel 13 by the pipe or tubing member 22 which also serves

2

as a fluid conduit for conducting hydraulic fluid to the lifting piston. At the ends of the channel 13 two upright plates 23 are provided which are interconnected to the shaft or bolt 24 which serves as a pivotal support for the end of the hydraulic cylinder 25. The hydraulic cylinder 25 is connected by a flexible conduit or hose 26 to the pipe 22. The hydraulic cylinder 25 has a piston rod 27 which is connected to the arm 19. The cylinder 25 and piston rod 27 are of a construction similar to that used in a loader for tractor shown and described in my co-pending application Serial Number 758,299, filed July 1, 1947. That application also shows the construction of the lifting arm 19. Thus the owner of a loader for tractor may utilize the arms and pistons of the loader in the operation of the truck and wagon hoist.

At an intermediate point between the upright member 17 and one extremity of the channel 13 the channel 13 is provided with a pair of upright plates 28 and 29. The tops of these plates 28 and 29 are welded to a strip of metal 31 which also is welded to the top of the channel 13 between the end of the channel and the upright member 17. It may be seen from Fig. 3 that the one plate 28 and the channel 13 are provided with tapped openings for receiving cap screws 32 which pass through a flange 33 connected to a pipe 34 which extends between the two frames 11 and 12. As may be seen from Fig. 1 frames 11 and 12 are also interconnected adjacent their other ends by a cross-member 35.

The interconnecting pipe 34 serves as a bearing member for an equalizing crankshaft consisting of a sleeve 36 having a pair of arms 37 and 38. The arms 37 and 38 are connected to links 39 which in each instance are connected to the connection between the arm 19 and the piston rod 27. Coaxially arranged with the pipe 34 and the sleeve 36 is a pipe 41 which is connected at its ends by means of a hose or conduit 42 to the tubular frame member 22. The pipe 41 at one end is provided with a T connection 43 which is connected by a flexible conduit to a source of hydraulic power.

Each lifting arm 19 consists of a tubular member 44 having at one end an apertured plate 45 for making a pivotal connection to the piston rod 27 and the link 39. Welded to the tubular member 44 is a plate 46 which in turn is interconnected by a brace rod or plate 47 to the pipe 44. The plate 46 is provided with suitable apertures for receiving bolts which pass through a pivotal support 48 which has a bearing portion carried by the bolt 18. Each of the frames 11 and 12 is also provided with a stabilizing lever or link 49 which is pivotally connected to a suitable point on the upright member 16.

Mounted between the outer extremities of the arms 19 is a lifting cradle 51 formed of two parallel angle-irons 52 and 53 interconnected at their

intermediate portions by a flat plate 54. The ends of the angle irons 52 and 53 are interconnected by angle irons 55 and 56 which carry upright connecting members 57 and 58. Each of the upright interconnecting members 57 and 58 is provided with a bifurcated portion for receiving a cooperating pivotally connected member 59 secured to the upper extremity of the tubular member 44 of the arm 19. The inverted angle irons 52 and 53 being spaced apart engage the wheel of a wagon or truck in such manner as to securely cradle the wheel and to hold it securely.

The stabilizing links 49 are selected to be of such length and are pivotally mounted on the members 16 at such points that the cradle 51 will securely hold the wheels of the wagon or truck and yet the arc described by the axle of the wheels being raised will approximate an arc made when the axle of the wheel which is on the ground is fixed in a stationary position. Thus in spite of the fact that the radius of the arc shown in dotted line in Fig. 2 is less than the wheel base of the vehicle, the wheels which are on the ground do not move any substantial amount. The cradle, therefore, does not necessarily remain parallel to the ground but may tilt slightly so as to compensate for the effect of the length of the wheel base of the vehicle being greater than the arc described by the lifting arm 19.

While for the purpose of illustrating and describing the present invention a preferred embodiment has been illustrated in the drawings, it is to be understood that the invention is not to be limited thereby since such variations in the components employed and in their arrangement is contemplated as may be commensurate with the spirit and scope of the invention set forth in the accompanying claims.

What I desire to protect by United States Letters Patent is claimed as follows:

1. A vehicle hoist comprising a pair of parallel triangular frame members formed of tubular material, a portion of which serves as a hydraulic conduit, a pivoted lifting lever mounted at the apex of each frame member, each lever being of the bell crank type, a hydraulic cylinder and piston mounted on each frame member and connected to a lifting lever, an equalizing crank interconnecting said levers, said crank having a rotational axis located in the proximity of the base of said frame members, a hydraulic conduit interconnecting said frame members, a flexible conduit interconnecting each cylinder with the conduit portion of its associated frame, and a cradle mounted between the free ends of said levers for engaging both wheels of a vehicle axle.

2. A vehicle hoist comprising a pair of parallel triangular frame members formed of tubular material, a portion of which serves as a hydraulic conduit, a pivoted lifting lever mounted on each frame member near its apex, each lever being of the bell crank type, a hydraulic cylinder and piston mounted on each frame member and connected to a lifting lever, an equalizing crank interconnecting said levers, said crank having a rotational axis located in the proximity of the base of said frame members, a hydraulic conduit adjacent said base interconnecting said frame members, a flexible conduit interconnecting each cylinder with the conduit portion of its associated frame, a cradle for the wheels of a vehicle axle mounted between the free ends of said levers, and a stabilizing lever interconnecting each frame member with said cradle to preclude substantial tipping motion thereof.

3. A vehicle hoist comprising a pair of parallel triangular frame members each having a base and a vertical portion formed of tubular material, a portion thereof serving as a hydraulic conduit, a pivoted lifting lever mounted on each frame member adjacent the top thereof, each lever being of the bell crank type, a hydraulic cylinder and piston mounted on each frame member and connected to a lifting lever, an equalizing crank interconnecting said levers, said crank having a rotational axis located in the proximity of the base of said frame members, a hydraulic conduit interconnecting said frame members, a flexible conduit interconnecting each cylinder with the conduit portion of its associated frame, a cradle for the wheels of a vehicle axle mounted between the free ends of said levers, and a stabilizing lever interconnecting each frame member with said cradle for moving said cradle in a path so that the axle of the wheel of the vehicle supported thereby approximates an arc of a radius equal to the wheel base of the vehicle.

4. A vehicle hoist comprising a pair of parallel frame members each having a box frame base and a triangular vertical portion formed of tubular material, a portion thereof serving as a hydraulic conduit, a pivoted lifting lever mounted on the apex of each frame member, a hydraulic cylinder and piston mounted on each frame member and connected to a lifting lever, an equalizing crank interconnecting said levers by means of lever links, said crank having a rotational axis located in the proximity of the base of said frame members, a hydraulic conduit interconnecting said frame members, said conduit having its axis in the proximity of the rotational axis of said crank, conduit means interconnecting each cylinder with the conduit portion of its associated frame, a vehicle wheel engaging cradle mounted between the free ends of said levers, and a stabilizing lever interconnecting each frame member with said cradle.

5. A vehicle hoist for engaging a pair of wheels of a vehicle comprising a cradle for receiving said wheels, a pair of vertical parallel triangular frames formed with an integral hydraulic conduit, a bell crank lever mounted near the apex of each frame and connected at one end by a pivotal connection to said cradle, a hydraulic cylinder and piston carried by each frame and pivotally connected to the other end of said lever, a fluid conduit interconnecting each cylinder with the hydraulic conduit of its associated frame, an equalizing crank interconnecting said pistons, said crank having its axis of rotation in the proximity of the base of said frames, and extending there between, a conduit interconnecting the integral hydraulic conduit portions of said frames, and means for supplying hydraulic fluid under pressure to said conduit and said hydraulic cylinder.
